UNITED STATES PATENT OFFICE.

LAWRENCE D. MORTON, OF SANDUSKY, OHIO, ASSIGNOR TO THE HINDE & DAUCH PAPER COMPANY, OF SANDUSKY, OHIO, A CORPORATION OF OHIO.

HANDLE FOR PAPER BOXES.

1,154,043.

Specification of Letters Patent. Patented Sept. 21, 1915.

Application filed January 15, 1915. Serial No. 2,880.

To all whom it may concern:

Be it known that I, LAWRENCE D. MORTON, a citizen of the United States of America, residing at Sandusky, in the county of Erie and State of Ohio, have invented certain new and useful Improvements in Handles for Paper Boxes, of which the following is a specification, reference being had therein to the accompanying drawings.

10 It is the object of the invention to obtain a construction of handle for use on paper boxes and cartons which is adapted to be quickly applied and which will distribute the stress so as to avoid tearing of the paper.

15 In the drawings: Figure 1 is a perspective view showing the manner of engaging the handle with the box or carton; Fig 2 is a cross section through the wall of the box to which the handle is secured; Fig. 3 is a cross 20 section through the fastener for the handle; and Fig. 4 is a longitudinal section therethrough.

A is a strap or tape formed of suitable fabric or other flexible material. B are fasteners secured to the opposite ends of said tape which are adapted to be inserted through slits C formed in the wall D of a paper box or carton. The fasteners B are in the form of comparatively thin flat plates, 25 and are so attached to the handle A that the latter extends from the central portion of one side of the plate. Thus when stress is placed upon the handle, the flat side of the plate B will be drawn against the face of the 30 paper wall, distributing the stress over a considerable area and preventing the tearing of the paper.

The fastener B is preferably constructed as shown in Figs. 3 and 4, in which E is a central member formed of thin sheet metal around which the end of the tape A is wrapped. F is a surrounding member also formed of sheet metal and folded to embrace the member E, with the opposite edges of the 45 fold meeting at the center of the plate and forming a slit for the outwardly-extending portion of the tape. The ends of the member E are then bent or folded at G over the ends of the folded member F, and the several plies are pressed into close proximity to each other. Thus the tape can be securely clamped between the members E and F and will extend out through the central portion of the slit. This leaves a bearing portion at 50 both sides of the tape and extending for a

considerable distance beyond the edges of the tape, as shown in Fig. 4.

In use, the member B may be readily inserted through a slit in the paper box, drawing the tape through with it, after which the 55 tape is drawn back to hold said member B in contact with the face of the paper wall. In this position the longitudinal dimension of the member B is parallel to the slit and extends beyond each end of the latter so as 60 to form a bearing upon the unslotted portion of the paper as well as upon the portions on opposite sides of the slit.

What I claim as my invention is:—

1. An attachable handle for paper cartons and similar articles, comprising a flexible tape or strap, and a flat member secured to the end of the tape adapted for insertion through a slit in the wall of the carton to draw the tape therethrough, said member being of lesser width and greater length than the slit and centrally attached to said tape to form a bearing surrounding the slit.

2. An attachable handle for paper cartons and similar articles, comprising a flexible tape or strap, and a flat member attached to the end of said tape adapted for insertion through a slit in the paper wall, said member being of lesser width and greater 75 length than the slit and the attachment of the tape thereto being in the central longitudinal plane thereof.

3. An attachable handle for cartons and similar articles, comprising a flexible tape 80 or strap and a member in the form of a thin flat plate, to which said strap is attached in the central longitudinal plane thereof, said member being insertable through a slit in the paper wall, and when a tension is placed 85 on said strap, forming a bearing surrounding said slit and extending beyond the opposite ends thereof.

4. An attachable handle for paper cartons, comprising a flexible tape or strap and a member attached to the end of said strap, comprising a central core around which the strap is wrapped and a member folded about said core and clamping the strap thereto, the opposite edges of said member meeting in the central plane and forming a slit for the outward passage of the tape.

5. An attachable handle for paper cartons and similar articles, comprising a flexible tape or strap and a member at 105 110

tached to the end of said tape comprising a core member about the center of which the tape is wrapped and a member folded about said core and clamping the tape thereto, 5 forming a central slit for the outward passage of the tape, and the ends of said core member being folded over the ends of the outer member.

6. An attachable handle for cartons and 10 similar articles, comprising a flexible tape or strap and a member attached to the end of said tape adapted to be inserted through

a slit in the paper wall, to draw said tape therethrough, said member being so attached as to lie in a plane parallel to the 15 side of the slitted wall and to extend beyond the opposite ends and upon opposite sides of said slit.

In testimony whereof I affix my signature in presence of two witnesses.

LAWRENCE D. MORTON.
